GAS PILOT VALVE

Herbert J. Long, Springfield, Mass., assignor to
United American Bosch Corporation, Springfield,
Mass., a corporation of New York

Application March 19, 1937, Serial No. 131,814

2 Claims. (Cl. 158—117.1)

This invention relates to a pilot burner of the type adapted to cut off the supply of gas to both the main burner and the pilot burner in the event the flame at the pilot burner tip becomes extinguished.

It is one of the objects of this invention to provide a burner of this type in which the flow of gas to the pilot burner may be readily and delicately adjusted while the pilot is in operation.

It is a further object of the invention to provide a structure which is simple and therefore inexpensive in manufacture yet durable and economical in use.

It is a further object of this invention to provide a safety pilot of this type in which the thermostat is not exposed directly to the flame of the burner nor to the gas flowing thereto. To this end the pilot burner is mounted on and above the thermostat housing and heat from the burner is conducted downwardly thereto by way of an integral metallic structure, while the gas supply for the pilot is conducted thereto by a passage separate therefrom. The thermostat device is thereby protected both from the direct heat of the flame of the pilot and also from impurities in the gas flowing to the burner which might otherwise affect its durability and efficiency.

The above and other objects and features of the invention insofar as they are not obvious to those skilled in the art, will be fully set forth in the following detailed description taken in conjunction with the accompanying drawing, in which:

Fig. 1 is a top plan view of a device constructed in accordance with the invention; Fig. 2 is a side elevation thereof; Fig. 3 is a section taken on line 3—3 of Fig. 1; Fig. 4 is a section taken on line 4—4 of Fig. 1; Fig. 5 is a detail showing a longitudinal section through the burner tip; Fig. 6 is a fragmentary section taken on the line 6—6 of Fig. 1; and Fig. 7 is a detail showing a longitudinal section through a modified form of burner tip.

Referring to the drawing, reference numeral 1 is a casting forming an L-fitting the lower branch 2 of which is internally threaded for connection with a suitable source of gas supply, and the other branch 3 of which is internally threaded for connection with a gas burner which, it will be understood, is disposed in close proximity to the pilot. In alignment with the passage formed by the lower branch 2 of the L is an internally threaded opening 4 in the upper portion of the casting 1 adapted to receive an externally threaded valve plug 5. An annular boss 6 of lesser external diameter than the diameter of the threaded portion of the valve plug 5 projects downwardly

therefrom, and the lower outer edge thereof is seated upon an internal shoulder 7 formed in the casting 1. The inner lower edge of the annular boss 6 provides a seat for a valve 8, the stem 9 of which projects upwardly through a central bore 5 in the plug 5. An externally threaded annular boss 10 projects upwardly for a short distance from the upper surface of the plug 5 and extends through an opening 11 in the lower half 12 of a sheet metal housing for a disc thermostat 13. A nut 14 on the annular boss 10 is adapted to act through a packing 15 to securely clamp the housing portion 12 to the valve plug 5. The valve stem 9 has a reduced end portion 16 which is externally threaded and projects through a central opening 15 in the disc 13 to secure said disc by threaded connection with a nut 17 integral therewith. The disc 13 is clamped between the lower housing member 12 and a similar upper housing member 18. The upper housing member has a central opening 19 and a pilot burner 45 is supported thereon and attached thereto by means of an internally and externally threaded bushing 20 which projects upwardly through the opening 19 and is provided with an outwardly extending flange 21 25 on the lower end thereof for contacting the inner surface of the housing member. This housing member is clamped between the flange 21 and the lower end of a burner support member 22, by screwing the bushing 20 into a longitudinal bore 30 23 of the member 20 the lower end of which is provided with internal threads for this purpose.

The casting 1 is also provided with a lateral bore 24, which opens into the gas inlet passage at a point below the valve 8. The outer end of bore 24 is closed by a valve plug 25, which is screw-threaded thereinto and which carries a valve 26 having a stem 27 which projects outwardly through a bore 28 in the valve plug. A spring 29, surrounding the outer end of the valve stem, acts upon a push button 30, which is threaded to hold the valve 26 against the seat formed in the valve plug and normally close communication between the passage formed by the lateral bore 24 and a passage 31 formed in the valve plug, which leads to an upwardly extending passage 32 formed in the casting 1. Passage 32 is threaded in its upper portion to accommodate external threads on a tubular member 33 which forms a lighting torch. The tubular member 33 has a central passage 34 which is closed at its upper end and is provided with a plurality of lateral jet orifices 35 one of which is directed toward the thermostat housing 55

18 and another of which is directed toward the pilot burner.

The casting 1 is also provided with passage 36 which opens into the interior thereof at a point above the valve 8 and extends angularly to a horizontally extending passage 37 formed in a raised portion 38 on the side of the casting 1. The other end of the passage 36 is closed by screw plug 39 and within the passage covered and protected by the screw 39 is an adjusting valve 40 for controlling the flow from the passage 37 to an upwardly extending passage 41. In the form shown the adjusting valve 40 is of the type in which rotation of the valve moves a groove in the side wall thereof into and out of registry with the passage 41, thereby more or less obstructing the flow therethrough. It will be understood that the valve might be of the type in which longitudinal motion thereof more or less obstructs such passage. A tube 42 extending partially into the passage 41 and sealed therewith by pressure plug 43 extends outwardly beyond the casting 1 and is bent to connect at its opposite end with a passage 44 of a burner member 45. The burner member 45 is preferably formed integrally with the support member 22 to facilitate the conduction of heat to the thermostat. The burner member is provided with an outwardly flaring flange 46 at one end thereof and the passage 44 is enlarged at this end to accommodate a jet plug 47. The jet plug 47 has a longitudinal passage 48 opening into passage 44 and terminating short of the end thereof. Jet passages 49 extend angularly from the passage 48 and are directed toward the flange 26.

A modified form of burner tip such as shown in Fig. 7 may be used where it is desired that the tip project vertically rather than horizontally. In this view similar reference numerals primed indicate parts similar to the unprimed reference numerals of Fig. 5, and the operation of this will be obvious from the description of the device with the burner of Fig. 5.

In operation the pilot is first ignited by holding the valve 26 in open position and igniting the lighter torch 33. The heat of the flame from the lighter torch causes the disc thermostat 13 to open the gas valve 8. Gas is thereupon supplied to the main and to the pilot burners which are ignited by the flame projected from the torch. The supply of gas to the lighter torch may now be discontinued. As long as the pilot is burning the valve 8 will remain in open position due to the heat conveyed thereto from the burner 45 through the burner support 22 which is integral with the burner. It will be seen that supplying the fuel to the pilot burner in the manner shown rather than through the disc thermostat

13 and the burner support 22 as in the usual constructions, permits the provision of a means for adjusting the quantity of gas flowing to the pilot burner from a convenient point at one side of the casting. At the same time the flow of gas through the disc thermostat is avoided, thus obviating the possibility of corrosion or other injury to this member through such source.

Though this invention has been described in connection with but a single embodiment thereof, it will be obvious that other embodiments within the scope of the following claims will occur to those skilled in the art and furthermore, while the device has been shown in its preferred positioning it will be obvious that it may be disposed in other positionings and the use of the terms "above", "below", "upper", "lower" and the like are used for convenience in the description of the form shown and are not limitations with respect to the positioning of the parts described.

What is claimed is:

1. A gas pilot control comprising a casting forming a valve housing having a passage extending therethrough, one end of said passage providing a connection to a source of supply, a valve plug closing the opposite end of said passage, an annular boss extending from said valve plug providing a seat, a valve coacting with said seat, means providing a gas outlet connected with the space in said casting above said valve, said boss having lateral openings providing communication with said space, a thermostat housing mounted upon said plug, a thermostat within said thermostat housing in heat conducting relation thereto adapted to actuate said valve, a pilot burner mounted upon and in heat conducting relation to said thermostat housing, and a tube extending from said burner externally of said thermostat housing and communicating with the space above said valve.

2. A gas pilot control comprising a casting forming a valve housing having a passage extending therethrough, one end of said passage providing a connection to a source of supply, a valve plug closing the opposite end of said passage, a valve having a stem extending through said plug, a thermostat housing supported upon said plug surrounding the projecting end of said valve stem, a thermostat in said housing coacting with said valve stem, a burner support mounted upon said thermostat housing, a pilot burner integral with said burner support, a tube forming a passage extending from said burner externally of said thermostat and communicating with the space above said valve, and means forming a passage for the discharge of the main gas supply from the space above said valve.

HERBERT J. LONG.
